Specification for Design.

Patented May 3, 1921.

Application filed June 21, 1920. Serial No. 390,660. Term of patent 7 years.

To all whom it may concern:

Be it known that I, JAMES LOWERY, a citizen of the United States, residing at Euclid, county of Cuyahoga, and State of Ohio, have invented a new, original, and ornamental Design for Vehicle-Tops, of which the following is a specification, reference being had to the accompanying drawing, forming part hereof.

The figure is a side elevation of a top showing my new design, the coöperating portion of the vehicle being shown in dot-and-dash lines.

I claim:

The ornamental design for a vehicle top as shown,

JAMES LOWERY.
